UNITED STATES PATENT OFFICE.

WILNER E. JOHNSON, OF BROOKLYN, NEW YORK, ASSIGNOR TO MEGOSIN COMPANY, INC., A CORPORATION OF NEW YORK.

HAND-BRAKE.

1,113,999.

Specification of Letters Patent. Patented Oct. 20, 1914.

Application filed June 17, 1914. Serial No. 845,627.

To all whom it may concern:

Be it known that I, WILNER E. JOHNSON, a citizen of the United States, and residing in the borough of Brooklyn, county of 5 Kings, and State of New York, have invented certain new and useful Improvements in Hand-Brakes, of which the following is a full and clear specification.

This invention relates to hand brakes for 10 railway or similar vehicles and has for its primary object to provide an improved construction, combination and arrangement of parts in a brake, in virtue of which said parts are normally disposed within small 15 compass and out of the way of passengers or others that may be passing through the car.

More especially, the invention is applicable to street railway cars or cars which handle crowds that are getting off and on at frequently recurring intervals. As a preferred embodiment of my invention, I have shown 20 its adaptation to a subway car in which the column between spaced doorways of said car 25 is employed to mount the brake-operating mechanism.

Further and more specific objects of invention will appear in the specification and claims, reference being had to the accompanying drawings in which,

Figure 1 is a side elevation of the preferred embodiment of my invention, parts being broken away and parts shown in section; Fig. 2 is a top plan view of the same, 35 parts being broken away and parts shown in section; Fig. 3 is a fragmentary section on the line III—III, Fig. 2, parts being shown in elevation; Fig. 4 is an end elevation taken from the right of Fig. 1.

In the preferred embodiment shown in the drawings, the brake-staff 1 is suitably mounted with respect to the floor 2 of the car, and carries adjacent the floor 2 a ratchet wheel 3 which is adapted to be held by a 40 pawl 4 mounted on a stud 5. The upper end of the brake staff 1 is reduced in diameter somewhat and provided with facets 6 upon which is removably seated a sleeve 7 which is similarly formed, so that relative rotation between these parts will not occur. The periphery of the sleeve 7 is provided with ratchet teeth 8 into engagement with which the pawl 9 is moved when the hand lever, to be hereinafter referred to, is drawn out-

wardly from the wall of the car. The sub- 55 way car, of which fragmentary portions are indicated on the drawings, is provided with lateral doorways 10, which are spaced longitudinally of the car for the accommodation of doors 11. Interposed between the doors 60 11 is a hollow sheet metal column 12, in the inner wall of which is provided an opening in which is mounted a recessed portion 13 of a plate provided with flanges 14 secured to said inner wall around the edges 65 of said opening. As shown best in Figs. 1 and 3, the recessed plate just referred to is provided with vertically spaced bearings 15 within which the upper end of the brake-staff 1 is journaled. Suitable means for operably connecting the hand lever to the 70 brake staff are provided by constructing the hand lever to comprise housing 16, which incloses the operating connection between the hand lever and the brake-staff, forked 75 branches 17 which project from said housing 16, and a handle grip 18 which is carried between the branches 17. Vertically spaced bosses 19 on the upper and lower walls of the housing 16, serve to pivotally mount the 80 hub portion 20 of a ratchet pawl 9, said pawl being provided with a tail piece 21 which is deflected outwardly, as shown in Fig. 2. Threaded into the inner wall of the recessed plate 13, is an abutment 22 against which 85 the tail piece 21 is thrown when the hand lever is in its extreme position adjacent the inner wall of the car, as shown in full lines in Fig. 2. Under this condition, the pawl 9 is retracted from the ratchet 8. Interposed 90 between the tail piece 21 and the opposite lateral wall of the housing 16, is a spring 23 which normally tends to hold the pawl 9 into engagement with the teeth 8. In consequence, whenever the hand lever is moved 95 into the position shown in dotted lines in Fig. 2, the pawl 9 engages the ratchet 8 and imparts a clockwise rotation to the brake-staff 1. By an inspection of Fig. 2, it will be noted that the outer end of the housing 100 16 is suitably formed to provide a nose or corner 24, which is adapted to be releasably engaged by a latch 25 which is pivotally mounted on a pin 26 within the recess of the plate 13. A spring 27 which is interposed 105 between the plate 13 and an arm 28 carried by the latch 25, serves to resiliently press the latch 25 over the nose 24 to retain the

hand lever against the inner wall of the car when not in use.

The method of operation of my improved hand brake will now be readily understood and briefly described as follows: When it is desired to brake the car, the operator by grasping the grip 18 moves the hand lever in a clockwise direction, according to Fig. 2. As said lever swings into the position indicated in dotted lines in Fig. 2, the pawl 9 is released from engagement with the abutment 22, the spring 23 forcing it into connection with the ratchet 8 and imparting a clockwise rotation to the brake-staff 1. This action is repeated as many times as desired. When sufficient power has been applied to the brakes, the return of the hand lever into position shown in full lines in Fig. 2, forces the pawl 9 into position to release the ratchet wheel 8 and makes it possible to release the brake-staff 1 by disengaging the pawl 4 from the ratchet wheel 3. From an inspection of Fig. 2, it will be seen that the housing 16 projects laterally on the side adjacent to the inner wall of the car and when in the position shown in full lines in Fig. 2, extends into the recess in the plate 13. This construction is compact and disposes of the moving parts of the ratchet connection and hand lever attachments in such a way as to occupy very little space, while at the same time providing a simple automatic construction for releasing the hand lever from the brake-staff at the end of each braking action. Furthermore, the latch 25 serves to retain the hand lever in a position in which it does not encumber the space of the car.

I claim:

1. In a car, an inner wall provided with a recess, a brake-staff journaled on an axis adjacent said wall, a hand lever having one end journaled on the axis of said brake-staff, and means adapting said hand lever to move said brake-staff on its axis when said hand lever is moved away from said inner wall, said means including parts mounted on said hand lever and extending toward said inner wall, said parts being housed in said recess when the hand lever is nearest to said wall.

2. In a car provided with a recess in an inner wall thereof, a brake-staff journaled adjacent to said wall, a ratchet on the upper end of said brake-staff, a hand lever having one end oscillatably mounted adjacent to the upper end of said brake-staff, and provided with a projecting arm, said pawl being disposed within said recess when the hand lever is nearest said wall, and an abutment in said recess adapted to engage said arm to release said pawl from said ratchet.

3. In a car, provided with adjacently disposed doorways, and an upright column between said doorways, the combination with the inner wall of said column provided with a recess, of a brake operating hand lever pro-

vided with attachments, said attachments being disposed within said recess when said hand lever is disposed adjacent to said wall.

4. In a car having an inner wall provided with a recess, a brake-staff mounted adjacent said wall, a hand lever carried by said brake-staff and having ratchet connection therewith, portions of said ratchet connection being mounted on said hand lever and extending into said recess when the hand lever is against said inner wall, and means mounted within said recess for releasing said ratchet connection when said hand lever is adjacent to said wall.

5. In a car, having an inner wall provided with a recess, a brake-staff having its axis adjacent said wall, a hand lever having a ratchet connection with said brake-staff, and a housing for said ratchet connection having a protuberant portion extending toward said wall, said housing being carried by said hand lever and entering said recess when the hand lever is adjacent to said wall.

6. In a car having an inner wall provided with a recess, a brake-staff adjacent said wall, a hand lever having ratchet connection with said brake-staff and carrying a housing for said ratchet connection protruding into said recess when said hand lever is adjacent thereto, and a dog pivoted in said recess, said dog being adapted to yieldably engage said hand lever.

7. In a car, the combination with a brake-staff provided with a ratchet wheel, of an operating lever therefor provided with a housing for the upper end of said brake-staff, said housing being provided with coaxial bosses on opposite inner walls thereof, a pawl pivotally supported between said bosses and adapted to coöperate with said ratchet, said pawl being provided with a tail piece, and an abutment against which said tail piece is moved to release the pawl from said ratchet when said hand lever is at one extreme of its movement.

8. In a car having an inner wall provided with a recess, the combination with a brake-staff mounted adjacent said inner wall, of a ratchet wheel carried by said brake-staff, a hand lever having a housing for said ratchet wheel, said housing being extended on the side toward said inner wall of the car and into said recess when the hand lever is at that extreme of its movement, a pawl pivotally mounted in said housing, said pawl being provided with a tail piece deflected toward said inner wall, and an abutment mounted within said recess to engage said tail piece when the hand lever lies adjacent said inner wall, said pawl being thereby disengaged from the ratchet.

9. In a car, having an inner wall provided with a recess, the combination with a brake-staff mounted adjacent said inner wall, of a ratchet wheel carried by said brake-staff,

- a hand lever having a housing for said ratchet wheel, said housing being extended on the side toward said inner wall of the car and into said recess when the hand lever is at that extreme of its movement, a pawl pivotally mounted in said housing, said pawl being provided with a tail piece deflected toward said inner wall, an abutment mounted within said recess to engage said tail piece when the hand lever lies adjacent said inner wall, said pawl being thereby disengaged from the ratchet, and a latch suitably mounted within said recess to releasably engage said hand lever in its extreme position. 5
10. In a car having an inner wall, the combination with a brake-staff mounted adjacent to said inner wall, of a hand lever for operating said brake-staff, ratchet mechanism connecting said hand lever to said brake-staff, said hand lever comprising a housing for said ratchet mechanism, forked branches extending from said housing and a handle mounted between said branches, 20 said branches being arranged in the same plane parallel to said inner wall to permit the hand lever to lie thereagainst. 25
11. In a car having an inner wall provided with a recess, a brake-staff, a hand lever, ratchet mechanism connecting said brake-staff and hand lever, said hand lever comprising a housing for said ratchet mechanism and branches for holding a handle extending from said housing, and a latch suitably mounted in said recess to releasably engage the end of said housing between said branches. 30
12. In a car having an inner wall provided with a recess, a brake-staff, a hand lever, ratchet mechanism connecting said 35
- 40
- brake-staff and hand lever, said hand lever comprising a housing for said ratchet mechanism and branches for holding a handle extending from said housing, and a latch suitably mounted in said recess to releasably engage the end of said housing between said branches, said housing being disposed to overhang on the side adjacent to said wall and to enter said recess when said lever arm was moved into a position near said wall. 45
13. In a vehicle having an inner wall provided with an opening, a recessed plate removably mounted in said opening, a brake-staff adjacent said inner wall, a hand lever surmounting said brake-staff and having a housing projecting laterally therefrom, the recess in said plate being adapted to accommodate the projecting housing when said hand lever is moved against said inner wall, and means within said housing for connecting said hand lever to said brake-staff. 50
14. In a vehicle having an inner wall provided with an opening, a recessed plate removably mounted in said opening, a brake-staff adjacent said inner wall, a hand lever surmounting said brake staff and having a housing projecting laterally therefrom, the recess in said plate being adapted to accommodate the projecting housing when said hand lever is moved against said inner wall, means within said housing for connecting said hand lever to said brake-staff, and means mounted in the recess in said plate for making and breaking the connection between said brake-staff and hand lever. 55
